UNITED STATES PATENT OFFICE

EVERETT P. LARSH, OF VANDALIA, OHIO, ASSIGNOR TO THE MASTER ELECTRIC COMPANY, OF DAYTON, OHIO, A CORPORATION OF OHIO

DESIGN FOR AN EXERCISING-MACHINE FRAME

Application filed November 21, 1929. Serial No. 33,519. Term of patent 7 years.

To all whom it may concern:

Be it known that I, EVERETT P. LARSH, a citizen of the United States, residing at Vandalia, Montgomery County, Ohio, have invented a new, original, and ornamental Design for an Exercising-Machine Frame, of which the following is a specification, reference being had to the accompanying drawings, forming a part hereof.

The figure of the drawing is a perspective view of an exercising machine frame showing my new design.

I claim:

The ornamental design for an exercising machine frame substantially as shown.

In testimony whereof, I have hereunto set my hand this 5th day of Nov. A. D. 1929.

EVERETT P. LARSH.
